KNITTING APPARATUS

David H. Young, Philadelphia, Pa., assignor to
Artcraft Silk Hosiery Mills, Inc., Philadelphia,
Pa., a corporation of Delaware

Application March 16, 1934, Serial No. 715,854

2 Claims. (CL 66—126)

This invention relates to knitted hosiery and more particularly to improvements in the method of and apparatus for knitting the same.

It has been recognized by those familiar with the hosiery art that it is often the case in knitting hosiery from a single length of yarn that shadows, rings and other such disfiguring conditions are present in the finished stocking, this being due primarily to variations in the weight, thickness and denier of the yarn employed. Natural silk yarn is particularly subject to these variations because it is difficult, if not impossible, to control the work of the silk worm as to insure the production of a substantially uniform filament of silk. It frequently occurs that in a continuous length of silk yarn successive portions thereof are of different thicknesses with the result that when two or more successive courses of a knitted fabric are knitted of a portion of the yarn which varies from the average weight or denier thereof, a shadow, stripe or ring effect is produced in the fabric. Of course, if the variations in weight or denier of the silk yarn were distributed throughout the stocking fabric in such manner that no two or more successive courses were knitted of yarn of the same weight or thicknesses, the objectionable condition above referred to would not be obtained. While various attempts have been made from time to time to remedy this objectionable condition, none of them have been entirely satisfactory and it is accordingly among the objects of the present invention to obviate the foregoing objections by the provision of an entirely new method of knitting a hosiery fabric in which a single carrier is employed for laying a pair of yarns along the needles of the knitting machine, it being a characteristic feature of this invention that the two yarns thus fed by the single yarn carrier are laid upon the sinkers and dividers in substantially parallel relation in such manner that together they form a single course of the knitted fabric in which any variations in the thickness, weight or denier of one yarn are largely offset by counterbalancing variations in the thickness, weight or denier of the other yarn.

A further object of the invention is to knit a hosiery fabric of two yarns arranged in substantially parallel relation, each yarn being so complementary to the other in weight, thickness and denier as to produce a finished fabric of uniformly even texture wherein rings, shadows, stripes and other such objectionable conditions are substantially eliminated.

Still another object of the invention is to provide a method of and apparatus for knitting a

hosery fabric in such manner that each course thereof is composed of two separate yarns arranged in substantially parallel relation, each yarn being delivered from a separate cone and the two yarns being commonly delivered by a single thread carrier to a substantially common point immediately in advance of the knitting needles.

Still another object of the invention is the provision of an improved construction of yarn carrier which is capable of delivering a pair of yarns to the knitting head of a knitting machine, the carrier being so designed as to maintain the yarns in separated relation throughout their travel from their sources of supply to a substantially common point located immediately adjacent the knitting head of the machine.

Other objects and advantages resulting from the present invention will be apparent more fully hereinafter.

The invention consists substantially in the combination, construction and relative arrangement of parts, as well as in the method of employing the same, all as will appear more fully hereinafter, as shown in the accompanying drawing, and as finally pointed out in the appended claims.

In the accompanying drawing:—

Figure 1 is a perspective view of a portion of a knitting machine in which the thread carrier as constructed in accordance with the present invention is employed;

Figure 2 is a perspective view of the improved yarn carrier;

Figures 3 and 4 are transverse sectional views taken along the lines 3—3 and 4—4 respectively of Figure 2;

Figure 5 is a side elevational view of the thread carrier;

Figure 6 shows a stocking knitted by the method of and with the thread carrier of the present invention, the encircled portion being an enlargement of the knitted fabric;

Figure 7 is a view of the lower portion of the yarn carrier showing a modified construction thereof; and

Figure 8 is a sectional view taken on the line 8—8 of Figure 7.

Referring now more particularly to Figure 1, it will be observed that the thread carrier 10 of the present invention is shown applied to a full-fashioned hosiery knitting machine of the type comprising the unusual sinker bed 11 having the alternately disposed sinkers 12 and the dividers 13. The needles 14 of the machine are respec-

tively disposed between the forwardly extending extremities 15 of the sinkers and dividers.

Inasmuch as the operation of the knitting machine has not been altered in any respect by the 5 present invention, it is not believed necessary for the purpose of the present invention to describe such operation in detail, it being understood that the construction of the machine and its operation, except for the thread carrier 10, are conventional. 10 The yarn carrier 10, which is adapted to move longitudinally of the sinker bed to lay the yarn upon the sinkers and the dividers along the needles 14, comprises a main body which is of gradually decreasing width from the upper toward 15 the lower end thereof. The upper portion 16 of the yarn carrier is bent upwardly, as at 17, and is provided at its upper extremity with a pair of oppositely extending apertured ears 18 for securing the carrier to the longitudinally reciprocable carrier bar (not shown) of the machine. 20 The lower portion 19 of the yarn carrier is bent downwardly, as at 20', with the result that when the carrier is properly mounted upon its reciprocable supporting bar the said portion 19 therefore 25 presents itself immediately in advance of the knitting head of the machine which is composed of the needles 14, the sinkers 12 and the dividers 13.

Formed in the upper portion 16 of the carrier 30 10 are a pair of laterally spaced substantially parallel grooves 20 and 21, these grooves extending preferably from the upper edge of the carrier to points just beyond the upper bend 17 thereof. Suitably fixed within the grooves 20 35 and 21 are a pair of upper yarn guide tubes 22 and 23 the lower extremities of which respectively terminate short of the lower ends of the grooves 20 and 21.

Formed in the lower portion of the carrier is 40 a groove 24 having the upwardly extending diverging sections 25 and 26. Secured to the carrier immediately above the upper extremities of the divergent portions 25 and 26 of the groove 24 are a pair of laterally spaced yarn guiding 45 eyes 27 and 28, while provided in the lower extremity or throat of the groove 24 is a centrally disposed yarn separator 29. Fitted within the lower portion 19 of the carrier is the bottom yarn 50 guide which may be in the form of a single tube 30 (see Figure 2) or in the form of a pair of small diameter tubes 31 and 32 arranged in parallel relation (see Figure 7).

The operating characteristics of the yarn carrier as just described is essentially the same as 55 the conventional yarn carriers insofar as its reciprocation along the knitting head of the machine is concerned. It differs, however, from the conventional yarn carrier in that it delivers two 60 yarns to the knitting head of the machine instead of the single yarn of the conventional yarn carrier. The yarns which are so delivered by the present dual yarn carrier are obtained from separate cones suitably mounted upon the knitting machine. The separate yarns so obtained from 65 the two cones are designated in the drawing as *a* and *b*, it being understood that these yarns *a* and *b* are preferably as substantially identical as it is possible to obtain under carefully supervised and controlled silk worm production and 70 subsequent spinning operations. Also, it will be understood that in the knitting of a fabric of certain weight, each of the yarns *a* and *b* are of such weight that combined they produce the desired weight of knitted fabric. Thus, each of the 75 two yarns may be of the same number of threads

or one yarn may be of a greater number of threads than the other.

Inasmuch as it is extremely unlikely for the 5 yarn of one cone to exactly match linearly through its length any unevenness in character of the yarn of the second cone, it will be apparent that by running the two yarns together through the same carrier the average weight, thickness or denier of the combined yarns will be quite uniform throughout each of the entire knitted fabric, thereby eliminating largely, if not entirely, the cause of shadows, rings and the like appearing in the finished fabric and making possible the production of a fabric of uniform texture throughout. Also, the use of two yarns laid side 10 by side along the needles to form each of the interlooped knitted courses of the fabric reduces very materially the liability of runs occurring, because it will require the breaking through of two 15 yarns at any point before a run can occur. 20

In the use of the above described yarn carrier, the yarns *a* and *b* are respectively threaded through the guide tubes 22 and 23 and the guide eyes 27 and 28, the yarn *a* being further maintained in separated relation from the yarn *b* by the divergently arranged guide grooves 25 and 26 and by the separator 29 located in the throat of the common groove 24, the two yarns being finally delivered to the knitting head of the machine through the bottom yarn guide of the carrier. 25 By so maintaining the two yarns in separated relation, it has been found that the yarns are maintained in a substantially common plane and do not become twisted together or otherwise displaced relatively to each other during the knitting operation; and that the knitted fabric, such as is shown in an enlarged scale in the insert of Figure 6, is extremely uniform in its texture and entirely free from disfiguring shadows, rings, 30 lines and the like. 35

A characteristic of the fabric knitted in accordance with the present invention is the entirely different effect which is produced by employing two or more separate and independent yarns in each knitted course, it having been observed, 40 for example, that when a pair of 2-thread yarns is so employed as against a single 4-thread yarn, the knitted fabric has the appearance of having been knitted of a single yarn of larger diameter than that of a 4-thread yarn. This is apparently due to the fact that when a plurality of yarns are employed in each course there results an apparent enlargement of the yarns which is not had when a single yarn is employed, in consequence of which there is obtained a more uniform 45 distribution and appearance of the yarn throughout the stocking fabric. The effect is substantially the same as when a relatively heavy yarn is employed, yet the fabric produced in accordance with the present invention and composed, 50 for example, of a pair of 2-thread yarns is at least as sheer and smooth and of as fine texture as can be obtained by the use of a single 4-thread yarn. 55

While the thread carrier of the present invention has been shown and described as having provision for delivering only two separated yarns to the knitting head of the machine, it will be obvious to those skilled in the art that by increasing the number of guide tubes and grooves 60 in the carrier the latter may be constructed to deliver more than just two yarns to the needles. 65

It will be understood, therefore, that the invention is susceptible of various such changes and modifications from time to time, all with- 70 75

out departing from the real spirit or general principles thereof, and it is accordingly intended to claim the same broadly, as well as specifically, as indicated by the appended claims.

5. What is claimed as new and useful is:—

1. In a yarn carrier of the character described, a main body member provided with an elongated yarn-receiving groove having divergent portions which merge at the delivery end of the member 10 to form a single throat, and a yarn separating member located in said throat for maintaining in separated relation a plurality of yarns passing through said throat and to insure their issuance from said delivery end of the member in intimately associated substantially parallel relation.

2. A yarn carrier of the character described comprising, in combination, a main body mem-

ber having a yarn delivering lower extremity which is adapted for disposition operatively in proximity to the knitting head of a knitting machine, a pair of yarn guiding tubes arranged in the upper end of said member in laterally spaced parallel relation, said member being provided with a yarn guiding groove having divergent upper extremities for respectively receiving in separated relation a pair of yarns delivered through said guiding tubes, said groove being downwardly convergent to provide a single restricted throat adjacent the delivery end of said member, and a yarn separator member in said throat for insuring passage of the yarns therethrough and their delivery therefrom in intimately associated substantially parallel relation.
